UNITED STATES PATENT OFFICE.

ROBERT LEE MOORE, OF GRAHAM, TEXAS.

SANITARY PROTECTOR FOR TELEPHONE MOUTHPIECES.

Application filed December 10, 1923. Serial No. 679,557.

To all whom it may concern:

Be it known that I, ROBERT LEE MOORE, a citizen of the United States, and a resident of the city of Graham, in the county of 5 Young and State of Texas, have invented certain new and useful Improvements in a Sanitary Protector for Telephone Mouthpieces; and I do hereby declare that the following is a full, clear, and exact description 10 of the same, reference being had to the accompanying drawings, and to the numerals of reference marked thereon, which form a part of this specification.

This invention relates to a sanitary protector for telephone mouth pieces.

Since telephones are ordinarily used by a large number of persons, there is always considerable danger of communicable diseases being transmitted by the user's proximity to or contact with the transmitter mouth piece. Attempts to eliminate this danger by the use of disinfectants or by various transmitter covers which have been heretofore made, have proven expensive or 25 ineffective.

It is therefore an important object of this invention to provide a sanitary mouth piece cover which obviates the above disadvantages, which may be provided at a 30 minimum of expense and which may be conveniently used for the purpose required.

It is a further important object of this invention to provide a protector of the class described which is particularly adapted for 35 the display of advertising indicia marked thereon.

Other and further important objects of this invention will be apparent from the disclosures in the specification and the accompanying drawings.

The invention (in a preferred form) is shown on the drawings and hereinafter more fully described.

On the drawings:

45 Figure 1 is a perspective view of a telephone transmitter provided with a sanitary protector embodying the principles of this invention.

Figure 2 is a plan view of a sheet from 50 which one form of the protector is made.

Figure 3 is a front elevation of the protector.

Figure 4 is an enlarged section with parts in elevation taken substantially along the 55 line 4—4 of Figure 3.

Figure 5 is a perspective view showing a

modified form of protector in position on a telephone transmitter.

As shown on the drawings:

The protector of this invention which is 60 adapted to be secured over the mouth piece 1 of a usual telephone transmitter 2, is constructed of thin paper or other suitable material and comprises a face portion 3 and bent-back flaps 4 on each of the vertical 65 edges of said face portion, said flaps 4 increasing in width toward the upper end of the face portion 3 and resiliently engaging the outside of the mouth piece 1 thereby holding the face portion 3 over the outer 70 end of said mouth piece and preventing the user's mouth from coming in contact therewith.

The protector may be formed either from a single or double sheet of material and, in 75 Figure 2, I have shown a blank from which the protector may be formed from a double sheet, the two portions of this double sheet being folded together along the line 5 and the flaps 4 being subsequently bent backwardly to engage the mouth piece 1 as shown in Figure 4.

In order to facilitate the transmission of sound waves through the protector, particularly in cases where the double thickness 85 protector is used, a series of apertures may be provided in the face portions 3 as shown at 6 and 7 in Figure 2.

The face portion 3 is ordinarily constructed so that a portion thereof of considerable area depends below the end of the mouth piece 1 and this depending portion is particularly adaptable to have advertising indicia marked thereon such as is indicated by the reference numeral 8.

It will of course be apparent that suitable advertising indicia may be marked on any part of the face portion 3 and, since this indicia is directly within the range of vision of the user and is forceably called to his attention, the space afforded for this purpose is valuable.

In Figure 5, I have shown a slightly modified form of protector wherein a face portion 3^a is provided with a rearwardly extending integral flap 9 and a downwardly bent integral bifurcated portion 10 on said flap which engages over the neck of the mouth piece 1 adjacent the transmitter and which holds said face portion 3^a over the 110 outer end of said mouth piece.

It will be apparent that in using the pro-

tector of this invention, it is only necessary to remove the same from a suitable container which may be placed near the telephone and affix it to the mouth piece 1 by a downwardly 5 sliding movement whereby the flaps 4 or the bifurcated portion 10 engage the outside of the mouth piece to hold the face portion 3 over the outer end thereof. After the user is finished talking on the telephone, the 10 protector may be thrown away and a new one similarly applied by subsequent user, whereby all danger of transmission of communicable diseases is obviated.

It will be apparent that the provision of 15 such a device affording space for advertising indicia constitutes an important feature since, as before stated, this indicia is always placed in a position where it is forceably brought to the attention of the telephone 20 user.

The sanitary protector of this invention, as will be apparent, may be very economically manufactured and, due to the fact that such valuable advertising space is afforded 25 thereby, it may be furnished to telephone users at very small expense.

I am aware that numerous details of construction may be varied without departing from the principles of my invention and I

therefore do not purpose limiting the patent 30 granted hereon otherwise than necessitated by the prior art.

I claim as my invention:

1. The combination with an outwardly flaring instrument mouth piece, of trap- 35 ezoidally shaped protective means covering the outer end thereof, and rearwardly bent integral means on the protective means folded from the upper to the lower edge of 40 said protective means engaging the mouth piece and holding the protective means in association therewith.

2. The combination with an instrument mouth piece, of protective means covering the outer end thereof comprising two sheets 45 of thin material each of said sheets having a plurality of apertures therethrough, and rearwardly extending means engaging the outside of the mouth piece and holding the protective means in association therewith. 50

In testimony whereof I have hereunto subscribed my name in the presence of two subscribing witnesses.

ROBERT LEE MOORE.
